(57) CLAIM

The ornamental design for an icon for a display screen, as shown and described.

DESCRIPTION

FIG. 1 is a front view of an icon for a display screen showing my new design; and,

FIG. 2 is a front view thereof, on an enlarged scale, the icon is shown separately for clarity of illustration.

The broken line drawing of a display screen in FIG. 1 is for illustrative purposes only and forms no part of the claimed design.

The G word mark is a Registered Trademark of Glance Networks, Inc.
